UNITED STATES PATENT OFFICE.

PAUL H. HORWITT, OF BROOKLYN, NEW YORK, ASSIGNOR TO INDEPENDENT PAPER MILLS, INC., OF BROOKLYN, NEW YORK, A CORPORATION OF NEW YORK.

HOLDER FOR STACKS OF SHEETS.

Application filed July 6, 1923. Serial No. 649,891.

To all whom it may concern:

Be it known that I, PAUL H. HORWITT, a citizen of the United States, and resident of the borough of Brooklyn, county of Kings, 5 city and State of New York, have invented certain new and useful Improvements in Holders for Stacks of Sheets, of which the following is a specification.

My invention relates to holders for stacks 10 of sheets and more particularly to holders for paper napkins, paper towels, toilet paper and the like and has for its object to provide a novel arrangement whereby a supply of such napkins, towels, toilet paper or the like 15 stacked in a novel manner is supported in such a way as to facilitate the removal of the terminal napkin or the like when desired, without requiring any special care to be exercised to avoid the unintentional removal of 20 more than one napkin or the like. Other more specific objects will appear from the description hereinafter.

Reference is to be had to the accompanying drawings which illustrate an example 25 of the invention without defining its limits and in which Fig. 1 is a plan view of a holder; Fig. 2 is a sectional view thereof on the line 2—2 of Fig. 1; Fig. 3 is a diagrammatic sectional view on an enlarged scale illustrating the novel arrangement of the napkins or the like in the stack and Fig. 4 is 30 a plan view of the novel stack.

The invention comprises essentially a holder which carries a supply of napkins or 35 their equivalent stacked in a novel manner, said stack consisting of napkins which alternately project beyond each other in opposite directions at opposite edges and some means whereby a pressure is exerted upon the projecting portions of the stack in such a manner as to separate an edge of the terminal napkin from the next succeeding napkin in 40 the stack. In other words, the stack of napkins or the like at its opposite edges is of 45 lesser density than the intermediate portion thereof so that as pressure is exerted upon this area of lesser density the same will be depressed and thereby cause the terminal napkin to be rendered independently 50 accessible at its one edge portion with respect to the next succeeding napkin. In its 55 illustrated example the holder is shown in the form of a stand comprising a base 5 from which a standard or pedestal 6 projects upwardly and carries at its upper end

a support 7. The latter carries the novel stack of napkins or the like in the manner indicated in Fig. 2; as illustrated in the drawing the napkins *a* of the stack project beyond the napkins *b* toward the right in 60 Figs. 2 and 3 while the napkins *b* similarly project beyond the napkins *a* toward the left in Figs. 2 and 3. With this arrangement the projecting portions of the napkins comprise an area of lesser density than that 65 of those portions of the napkins which overlap each other as is clearly shown in Fig. 3. The device comprises further a pressure-exerting means or member which, in the illustrated example, is shown in the form of a 70 floating rectangular frame the side members 8 of which are connected by means of end members 9; the side members 8, which may be said to constitute flanges, are of such dimensions as to correspond approximately 75 with the dimensions of the projecting portions of the napkins *a*, *b*, it being understood that the end members 9 do not rest upon any part of the stack of napkins. With this arrangement the frame or rather the side 80 members 8 and end members 9 thereof, define an open space 10 corresponding approximately in dimensions to the dimensions of the overlapping portions of the napkins *a*, *b*. To maintain the pressure-exerting member 85 in proper relation to the stack any suitable guiding means may be provided; in the illustrated arrangement this guiding means comprises flanges 11 which depend from the side members 8 and in some cases also from 90 the end members 9 and serve to enclose the stack of napkins or the like and thereby maintain the pressure-exerting member in its operative position and at the same time prevent the removal of individual napkins 95 or the like from said stack in any but the intended manner.

In practice the floating member or frame rests upon the stack of napkins or the like and through the medium of its side members 8 exerts a pressure upon the projecting portions of the napkins *a* and *b* or, in other words, upon the areas of lesser density of 100 said stack and thus causes the adjacent edge of the terminal or uppermost napkin or the like to be separated from the next succeeding napkin in the stack as illustrated in Fig. 1. In this manner the one edge of said terminal napkin is rendered independently 105 accessible with respect to the next succeeding 110

napkin and is thus capable of being easily fingered and grasped without special effort or care when it is desired to remove a napkin. Because of this fact it is a simple matter to remove individual napkins by withdrawing the same from the stack through the space 10, it being understood that the napkins *a* and *b* are alternately rendered independently accessible in the manner described as they alternately become the terminal napkins of the stack. The invention eliminates waste and at the same time makes it easy to procure as many napkins or other sheets as may be desired; in addition indistinct handling, for instance, of napkins, towels and the like is done away with so that the latter are protected against contamination and are maintained in a sanitary wholesome condition.

It will be understood that the illustrated arrangement may be varied as long as it includes a stack of napkins arranged in the manner described in combination with a means for exerting a pressure upon the projecting portions of the stack and a means or support for resisting said pressure in a manner to permit the terminal napkin to be tilted in the described way.

Various changes in the specific form shown and described may be made within the scope 30 of the claims without departing from the spirit of my invention.

I claim:

1. The combination of a support, a stack of sheets carried thereby, alternate sheets in 35 said stack being off-set and projecting beyond each other in opposite directions, and an apertured pressure exerting member resting upon the projecting portions of said stack and thereby tilting the terminal sheet 40 to project its free edge through said aperture and thereby facilitate the removal of said terminal sheet from said stack.

2. The combination of a stand, a stack of napkins carried thereby, alternate napkins being off-set and projecting beyond each other in opposite directions, and an apertured, rectangular frame having side members resting upon the projecting portions of 45 said napkins and thereby tilting the terminal napkin to project its free edge through said aperture and thereby facilitate the removal 50 of said terminal napkin from the stack.

In testimony whereof I have hereunto set my hand.

PAUL H. HORWITT.
